FASTENING DEVICE

May Spear, Jackson Heights, and Gladys Skluth,
Woodside, N. Y.

Application December 19, 1935, Serial No. 55,162

7 Claims. (Cl. 24—207)

This invention relates to slidable closure devices adapted for fastening the openings of bags, pouches, garments, and the like, and has for its main object to provide a device of this character in which a flexible element will lie alongside said opening being secured in appropriate depressions in spaced apart clips sliding on the edges of the opening.

Another object of this invention is to provide a device as characterized hereinbefore, of which only certain artistically arranged portions will be shown on the outer side of the article to which it is applied, while the major portion thereof will be concealed therein.

Still another object of this invention is to provide a sliding closure device of the type mentioned which is quick and reliable in operation, that is, in opening or closing the article or piece of garment to which it is applied.

Still a further object of this invention is to provide a closure device wherein slidable elements are moving in parallelism to one another and in a pre-determined spaced relation when the article is closed, and their movement is guided and controlled by a flexible element within the article to which the device is applied.

With this and other objects in view, as will be apparent as the specification proceeds, our invention mainly consists in slidable clip members on the outside of the opening in the bag, garment or the like, forcing the edges of said opening to one another, a portion of each of said clip members forming a channel or depression and there tightly embracing a flexible element by its pressure only, and being so secured thereto, so that when said clips are slid to one end, they will open the bag or garment, while if they are strung alongside of said opening as they are spaced along said sealed flexible member, they will tightly close the edges of said opening upon one another. In an embodiment of our invention said channel and said flexible element may be concealed within the bag or the like.

In the drawing forming a part of the specification and accompanying the same:

Fig. 1 is a perspective view of a bag in a closed position to which our invention has been applied;

Fig. 2 is a fragmentary partly sectional plan view thereof, while

Fig. 3 is a sectional detail, the section being taken on the line 3—3 of Fig. 2;

Figs. 4, 5, and 6, are fragmentary elevational respectively, sectional, views, showing a modification of our device, and

Figs. 7 and 8 show another modification.

Referring now more closely to the drawing by characters of reference, the numeral 10 indicates an article of manufacture in general, in this case being a bag, to which our invention is applied. 5 A mouth or opening 11 is provided for the bag having preferably beaded right-hand and left-hand edges 12 and 13. Slidable clip members 14 are arranged on the beads 12 and 13 in the manner to be described presently. Each bead has a 10 right-hand curved portion 15 and a left-hand curved portion 16 slidably but snugly encircling the respective beads 12 and 13. The right-hand curved portion 15 ends in a right-hand outer leg 17 and each left-hand curved portion 16 is 15 terminated in a left-hand outer leg 18. The two curved or arcuate portions 15 and 16, riding on the respective beads are interconnected with a downwardly extending loop 19, normally riding inside of the bag or other garment, to the opening 20 of which our device is applied, and a flexible strip-like member 20, like a cord, chain, etc., is tightly engaged by the loop portions 19, as shown; in this manner the individual sliding clips 14 are 25 fixedly secured and in spaced relation to one another on the cord or chain 20 within the bag or garment 10. The arcuate portions 15 and 16, constituting the double grips of each clip, are 30 illustrated as opening in substantially the same direction. This terminology should be understood 30 to mean that lines drawn from the bottom of each arcuate portion through the approximate center of each arc opening extend in substantially the same direction.

One end of the strip 20 may preferably be secured to the respective end wall in the opening 11 of the bag or garment, and it is obvious that if the clip nearest to the opposite end of the flexible member 20 is caused to slide towards the opposite end of the opening 11, all the clips 14 40 will be spaced along the opening 11 as shown in Figs. 1 and 2, and will thereby cause the beads 12 and 13 to be pressed to one another and so to close the opening 11. For better closure the clips 14 may be made of rather thin material and the 45 beads 12 and 13 somewhat yielding and elastic. If, on the other hand, clips 14 will be crowded near the end of the opening 11 in the bag to which the respective end of the flexible member 20 is secured, then of course, they will release 50 the two beads from one another and the bag will be open.

It will be seen that our invention may be applied not only to bags, as shown, but to any other article of manufacture having an opening there- 55

in with edges to be brought together or to be released from one another through the use of our device, whether such edges are beaded or not, or are flexible and elastic, or more or less rigid. It 5 also will be seen that we provide a slideable closure device of novel and artistic appearance, which is simple and cheap to manufacture, easy to apply and reliable and smooth in operation. Of course, the details of construction, material 10 and design of the individual clips as well as of the flexible member 20 may be greatly varied, like the legs 17 and 18 may be variously formed, and the inner loop 19 may preferably be smaller and more circular in cross section than shown in 15 Fig. 3.

In Figs. 4 to 6, we illustrate a modification of our device in which the right-hand and left-hand bent portions 21 and 22 of each clip 23 are directly interconnected with a bridge portion 24 20 outside of the beads 12 and 13. Said portion 24 may be made downwardly curved as shown in Fig. 6 or may be made entirely straight, and in the center portion thereof two parallel slits 25 and 26 may be provided and the material 27 between them bent upwardly so as to form a loop, best illustrated in Figs. 5 and 6. A flexible member 28 may be passed through the spaces between the loops 27 and the bridge members 24 whereupon said loop 27 may be securely pressed on the 30 flexible element 28 and each clip thus fixedly secured, in a desired spaced relation to one another on the flexible member 26. The use and operation of this device will be obvious from the drawing, and it is entirely similar to the one described in 35 connection with Figs. 1, 2, and 3, the only difference being that the flexible member 28 is exposed on the outside of the bag or garment and may be crowded to the one end of the opening or stretched along said opening according to whether 40 the bag or garment is to be opened or closed.

In Figs. 7 and 8, finally, we show still another modification of our invention, in which each clip 30 again has a channel shaped depression 31 into which is laid an appropriate flexible element 32, 45 like a chain, cord, etc., the sides of the depression being tightly pressed on said element 32 and the clip being secured thereon so that the flexible element will be exposed all along its length. The 50 walls of the depression may embrace the element 32 above its diameter, if round, or be bent over it, as indicated in the drawing, but the mere pressing of them on the element may also be sufficient to secure the clips at the respective place on the flexible element.

55 It will be understood that changes and variations may be made in the parts and combinations of our device and we hereby reserve all our rights to any and all such changes as are within the spirit of the invention and the scope of the 60 appended claims.

What we claim as new is:

1. A closure for an article having an opening with flexible beads extending along the edges thereof comprising a series of clips each having 65 adjacent arcuate inner portions opening in substantially the same direction and providing a double grip slidably engaging said beads, each clip including a portion intermediate the two gripping portions extending through the opening 70 a distance sufficient to cooperate with the end thereof to limit sliding movement of the clip along its supporting beads.

2. A closure for an article having an opening with flexible beads extending along the edges 75 thereof comprising a series of clips of arcuate

inner contour slidably engaging and supported by said beads, each end clip at least of the series having adjacent arcuate inner portions opening in substantially the same direction and providing a double grip slidably engaging the respective beads, said end clips including a portion intermediate the two gripping portions extending through the opening a distance sufficient to cooperate with the end thereof to limit sliding movement of the clip along its supporting beads. 10

3. A closure for an article having an opening with flexible beads extending along the edges thereof comprising a series of clips each having adjacent arcuate inner portions opening in substantially the same direction and providing a 15 double grip slidably engaging said beads, each clip including a portion intermediate the two gripping portions extending through the opening a distance sufficient to cooperate with the end thereof to limit sliding movement of the clip 20 along its supporting beads, and a flexible spacer element secured at spaced points along its length to the extended intermediate portion of each clip adjacent the extremity thereof, whereby the same is concealed from view. 25

4. A closure for an article having an opening with flexible beads extending along the edges thereof comprising a series of integral clips formed as independent arcuate portions opening in the same direction and adapted to embrace the beads respectively, the inner legs of said arcuate portions forming a double arm extending through said opening beyond the beads to form a stop cooperating with the end of said opening to limit the longitudinal sliding movement of the clips, and a flexible spacer element frictionally gripped at spaced points along its length between said inner legs adjacent the extremities thereof, whereby the same is concealed from view. 30

5. A clip for closing an opening, said clip comprising adjacent arcuate portions opening in substantially the same direction to provide a double grip adapted for slideable movement along adjacent supporting beads at opposite edges of said opening, said clip including a portion intermediate the two gripping portions, and lying substantially in the plane thereof, forming a common backing for the outer arcuate portion of each grip. 40

6. A closure for an article having an opening with flexible beads extending along the edges 50 thereof comprising a series of clips of arcuate inner contour slidably engaging and supported by said beads, each end clip at least of the series having adjacent arcuate bead-engaging portions opening towards one another at an angle within a range of infinity to 180° and providing a double grip slidably engaging the respective beads, said end clips including a portion intermediate the two gripping portions extending through the opening a distance sufficient to cooperate with the end thereof to limit sliding movement of the clip along its supporting beads. 55

7. A clip for closing an opening, said clip comprising adjacent arcuate portions opening towards one another at an angle within a range of infinity to 180° to provide a double grip adapted for slideable movement along adjacent supporting beads at opposite edges of said opening, said clip including a portion intermediate the two gripping portions, and lying substantially in the 60 plane thereof, forming a common backing for the outer arcuate portion of each grip. 65
